UNITED STATES PATENT OFFICE

162,781

BRA-TOP SLIP

Harvey Breitman, White Plains, N. Y., assignor
to United Mills Corporation, a corporation of
North Carolina

Application July 24, 1950, Serial No. 11,377

Term of patent 14 years

(Cl. D3—26)

To all whom it may concern:

Be it known that I, Harvey Breitman, a citizen of the United States, residing at White Plains, in the county of Westchester and State of New York, have invented a new, original, and ornamental Design for Bra-Top Slip, of which the following is a specification, reference being had to the accompanying drawing, forming part thereof.

In the drawing:

Figure 1 is a front elevation of a bra-top slip embodying my new design;

Figure 2 is a rear elevation.

The slip is shown folded flat in both views.

Referring to the drawing, the longitudinally extending bands are designed to be of decorative pattern, the specific nature of which is not a limitation of the invention.

The dominant feature of the design is the

ornamental appearance created by the combined effect of the longitudinal bands, which terminate at the waistline, with the centrally located zipper fastener which extends into the skirt area below the waistline.

I claim:

The ornamental design for a bra-top slip, as shown and described.

HARVEY BREITMAN.
